6 Claims. (Cl. 262—31)

1

This invention of improvements in and relating to the mining or winning of coal or other material is concerned with that method of operation (hereinafter termed method of the kind described) in which material is obtained by slicing or stripping it from a face by means of a device, herein for convenience termed a plough, which is traversed under power along the face and is provided with a wedge formation and a cutting edge to cut and lever away the material.

The plough has been constructed to slide over the floor and to direct coal on to a conveyor laid along the face and it has been kept up to the coal face by running it along the floor in contact with the conveyor structure which has been made appropriately heavy or massive for the purpose.

This method of operation, heretofore applied to coal mining, requires no undercutting of the coal, and no shot firing to break down the coal and the loading of the coal on to the conveyor has been effected by the plough concurrently with the cutting.

It is therefore a simple method and in appropriate circumstances has obvious advantages from the economical and practical stand-points.

The method has been used with success in the mining of soft coal which can be relatively easily sliced or stripped from the face. In the case of comparatively hard coal, however, difficulties arise in getting the plough to slice the coal owing to the resistance which the coal offers to cutting by the plough due to its hardness.

An object of the present invention is to provide an improved apparatus whereby the winning of hard coals or similar hard materials by the above method may be effectively carried out.

According to this invention a plough for use in the mining or winning of coal or other material by a method of the kind described and which plough as it proceeds along the face, is made to cut a kerf in the material to receive the thin end of the wedge formation of the plough, is characterised in that the kerf-cutting means of the plough comprises a series of spaced picks

10

5 or cutters having forward and backward movements with intervening upward and downward movements on the plough, said picks or cutters being operative by quickly repeated jiggling movements to cut away the material and form the kerf.

It will be realised that the picks or cutters

operate by movements somewhat similar to the

action of a miner's pick cutting a kerf, that is

to say, a rotary kind of digging or picking ac-

tion, and this is very effective for the forming

of the kerf for the plough in hard material.

Provision may suitably be made for varying the

length of the series of picks or cutters to enable

the plough to be used along faces of different

heights.

The invention will be more particularly de-

scribed in connection with the mining of coal

but it may be used for the winning of other

materials where similar conditions apply. It

may, of course, be applied to the mining of soft

coal if desired but as will be understood its more

particular purpose is the cutting of hard coal

or the like.

In order to enable the invention to be readily

understood reference is directed by way of ex-

ample to the accompanying drawings in which:

Figure 1 is a plan of coal-mine workings show-

ing a plough according to the present improve-

ments in operation on a coal face.

Figure 2 is a view to a larger scale showing

part of the coal face, a sectional plan of the

plough and a part, in plan, of a conveyor for

taking away the coal removed from the face.

Figure 3 is a rear elevation of parts shown in

Figure 2.

Figure 4 is a sectional elevation looking toward

the right-hand end of Figure 2 and the left-hand

end of Figure 3.

Figure 5 embodies a view similar to Figure 4

of a modified form of plough, and

Figure 6 is a fragmentary view, corresponding

to Fig. 3, illustrating another modification.

In Figure 1 a coal face 1 is shown in process

of being stripped by the plough 2 which is mount-

2

ed to travel along the conveyor 3 and is able to attack the coal in either direction of such travel. The conveyor is laid along the face 1 and extends at both ends into the gates or roads 4, 5. At the ends the conveyor, which is of sectional character after known practice, comprises sections which are embodied in portable structures 6, 7. These latter are fitted with wheels engaged with tracks 8, 9 so that they may be moved up as the face 1 advances, as indicated by the arrows. They may be so moved up by rotary sylvesters and haulage ropes, not shown, and at the same time as they are advanced, sylvesters or jacks are also applied, at spaced points indicated along the face by the lines 66, to the remainder of the conveyor structure between such end sections, so as to move that up as well. The plough 2 is of broadly known form in that it embodies a structure which has wedge-formations at 10, presented in opposite directions, which are operative to attack the coal face 1 somewhat like the edge end of a chisel. As will be understood, one wedge-formation of the plough 2 is effective in one direction of travel of the plough along the coal face and the other is effective when the movement of the plough is in the opposite direction. The coal removed by the plough is loaded thereby after usual manner on to the conveyor 3, suitably laid along the face parallel thereto. This conveyor is of chain-scraper type though a trough conveyor with belt could be used if desired.

The wedge formations 10 of the plough are disposed on a part 12 of the plough, Figures 3 and 4, which is carried on a main body or carriage 11 mounted to travel along the face on vertical and horizontal wheels 17, 18 respectively which run in channel-section track members 24 supported on side members 19 of the conveyor troughing 19, 21. The movement of the plough may be effected in any suitable manner as by haulage rope and winch though the preferred arrangement shown comprises an endless haulage rope 46 and is described in detail in the specification belonging to the concurrent patent application Serial No. 75,699, filed February 10, 1949.

The part 12 of the plough having the wedge formations 10, and which will for convenience be hereinafter referred to as the wedge part, overhangs the adjacent side of the conveyor troughing and extends substantially to the level of the floor 13 along the face 1 and nearly to the level of the roof. The wedge formations 10 are defined by renewable wedging blades 14 which in plan extend curvedly at an incline outwardly and rearwardly from the thin ends, and along the sloping part, of the wedge formations towards the main body 11, see Figure 2. Between the wedging blades 14 and end parts 15 of the main body 11 which slope down to floor level and serve to clean the floor of remnants of broken down coal, the plough has inclined ramps or scoops 16 which guide the main broken-down coal into the conveyor troughing.

For cutting a kerf 27, Figure 2, a vertical series of picks or cutters 28 is provided at each end of the wedge part 12 of the plough. These picks 28 are adapted to move in a circular path and for this purpose the sets of picks are mounted on a carrier 29 which is a sort of H-shaped structure of unitary form and has the picks disposed down the sides of the H on the outside edge see Figure 3. This carrier 29 is holed at two places (as at 39 Figure 2), on the cross-bar part of the H and spans across the outer ends of the two

wedging blades 14 of the wedge formations 10 of the plough 2. It may contact slidably with these ends of the blades 14 which are chamfered to provide flat surfaces 31 parallel with the coal face, see Figures 2 and 3. The holes 39 of the carrier 29 are fitted with bearing bushings 32 by which the structure is mounted on roller bearings 33 on a pair of eccentrics 34, carried on roller bearings 35 on short horizontal fixed spindles 36. Only one of the eccentrics and associated parts are shown in Figure 2 but it is believed that this will be sufficient for a proper understanding thereof. As will be seen from Figure 2, the cross-bar of the H-shaped carrier 29 is set back from the plane of the sides of the H to accommodate it in the outer compartment 37 of a doubly compartmented gear box which is supported on or embodied in the wedge part 12 of the plough body and extends along between the wedging blades 14. The spindles 36 are mounted in the walls of this gear box, and concentric hub parts 38 of the eccentrics 34 thereon carry gear wheels 39, see also Figure 3. These mesh with a central gear wheel 40 that is driven by a pinion 41 on a drive shaft (not shown) which extends into the inner compartment 42 of the aforesaid gear box and carries therein a gear wheel 43. The latter is meshed with gear wheels 44 mounted on the shafts of a pair of hydraulic or other motors 45 which extend over the conveyor 3 and form part of the main bridge-like structure 11 of the plough 2. There is an advantage in using two motors 45 for operating the picks 28 because they can be smaller than if a single motor were employed.

It will now be apparent that under the action of the drive from the motors 45, the eccentrics 34 will cause the picks 28 to have quickly repeated movements arising from the motion of the carrier 29 which will receive forward and backward movements with intervening upward and downward movements from the eccentrics. The sets of picks will suitably be withdrawn to the outer edge of the wedging blades 14 on the retractive or backward movement and be projected forward with a rotary motion from that edge to effect a cutting action on the downward movement component. Thus, each set of picks is able to form a vertical kerf in advance of the adjacent wedging blade 14, the kerf being constantly maintained and formed so that after each fresh cut when the picks are retracted, the outer end of the corresponding wedging blade 14 can nose itself into the kerf and exert leverage to break away the coal. Of course, it is only the forward set of picks 28 which is effective at any one time. On traverse of the plough in one direction one set of picks is operative, while in the opposite direction of traverse, the other set is effective for kerf cutting. Thus, in Figure 2 the set of picks on the left is operative to cut the kerf 27, the plough being traversed in the direction shown by the arrow. In Figure 3 the same set of picks appears retracted. The depth of the layer of coal removed by the plough may usefully be 12 inches in hard coal, though obviously the depth may be varied according to circumstances. The horizontal wheels 18 engaging the tracks 24 on opposite sides of the conveyor structure, in plan, are arranged at the four corners of a truncated isosceles triangle whose apex is on the face side of the conveyor. This arrangement is a desirable one to take up lateral stresses on the plough and thus prevent slewing of it with respect to the coal face during the operation of the plough. The wheels 17 will prevent the plough 2 from rising

on either side and the track members 24 with which they, and the wheels 18, engage lend weight to the conveyor structure which is of relatively heavy construction. Altogether, therefore, the wedge part 12 of the plough is kept substantially true with respect to the face 1 and as will be understood this makes for very efficient operation of the plough in cutting the kerf and slicing or stripping the face layers.

It will be apparent that the bridge-like main body 11 of the plough 2, as illustrated by Figure 4, extends from side to side over the conveyor at a good height. This form of the plough is intended for use on a normal coal seam, say 3' 6" (about 1 metre), high which is relatively high compared with some seams. At the height stated the bridging part of the plough is sufficiently high above the conveyor 3 to enable the cut coal, brought into the conveyor troughing by plough ramp or scoop 16, to pass beneath the bridge to delivery from the conveyor at the main gate 4, when the plough is operating during travel from the main gate 4 to the tail gate 5. Thus, the plough can be operative in both directions of traverse thereof along the face. In one direction, of course, i. e. with the plough moving unidirectionally with the conveyor scrapers or belt, the coal does not need to pass the bridge but when stripping the face by moving the plough in the opposite direction the coal scooped on to the conveyor must pass the plough and it does so through the bridge-form main body or carriage 11.

In a modified example for use with low seams, the conveyor construction and the mounting of the plough 2 on the conveyor may be similar to those above described as shown in Figure 5. The bridge-form main body or carriage 11 of the plough, however, is of flatter construction with the motors 45 for driving the kerf cutting picks 28 in a lower position. In this example, the bridge cannot be high enough for the coal to pass through it and therefore the plough is made operative to strip coal from the face in one direction of traverse only of the plough along the face, being flitted back to the starting point for a fresh cut.

According to a further modification and in order to provide for operations of the plough in higher seams, the carrier 29 of the picks 28, and the series of picks themselves, may be extended upwardly as shown by way of example at 100 in Figure 6. This provision can be carried out by fitting additional pick-carrying parts to the carrier or by making the side parts of the H-shaped carrier structure detachable and replacing them by pick-carrying parts but of extended height. Similarly, for lower seam ploughs (cf. Figure 5), detachable pick parts of this nature may be fitted.

The invention is not limited to the constructions thus particularly described because other modifications are possible without departing from the scope of the invention.

It is an advantage of the invention that the plough can be adapted to cut practically the full height of the seam because it provides for a clear cut of the face from top to bottom.

The apparatus described may be provided with features, other than those already referred to, to be found described in my specifications belonging to the concurrent patent applications Serial Nos. 75,698 and 75,699, each of which was filed February 10, 1949.

I claim:

1. A plough for stripping material from an upstanding face underground, comprising a carriage, a wedge formation at the forward end of said carriage, said wedge formation comprising a substantially vertical surface which is inclined towards said face and at the thin end thereof the wedge merges into an edge which is disposed to extend substantially parallel to said face in the top-to-bottom direction of such face, a carrier mounted on said carriage and extending at least substantially throughout the height of said edge in the region thereof, a series of spaced cutters disposed fixedly on said carrier in said region to project outwardly beyond said edge and so as to extend substantially parallel to said edge and substantially parallel to said face in the top-to-bottom direction thereof, and means on said carriage operative to impart to said carrier in a plane substantially parallel to said face quickly repeated forward and backward movements with intervening upward and downward movements on said carriage whereby the said spaced cutters are also given quickly repeated forward and backward movements with intervening upward and downward movements on said carriage with the whole series of them moving as one in a plane substantially parallel to said face.

2. A plough according to claim 1, further characterised by additional cutters disposed to extend said series of spaced cutters in its own plane at the top of the thin end of the wedge formation of the plough.

3. A plough according to claim 1 and wherein the plough has a wedge formation at each end thereof, further characterised by a carrier of unitary form having a series of spaced cutters at each of the opposite ends thereof, the said carrier extending, at both ends, at least substantially throughout the height, and parallel to the edge, of the adjacent thin end of the concomitant wedge formations in the region of such edge and the two series of spaced picks or cutters being presented in opposite directions and disposed on said carrier in said region and so that each series extends in the top-to-bottom direction of said face and substantially parallel thereto.

4. A plough for stripping material from a face underground, comprising a carriage having the form of a bridge, a wedge part disposed on the face side of said bridge and presenting wedge formations in forward and rearward directions, the thinner end of each of said wedge formations being disposed to extend substantially parallel to said face in the top-to-bottom direction of such face, a set of eccentrics revolvably mounted on said wedge part, a carrier mounted on said eccentrics and extending, at both ends, at least substantially throughout the height of the adjacent thinner end of the concomitant wedge formations in the region of the extremity of such thinner ends, two series of spaced cutters mounted on the respective ends of said carrier to project outwardly beyond said ends of said wedge formations, said two series being presented in opposite directions and disposed on said carrier in said region and so that each series extends substantially parallel to said face in the top-to-bottom direction thereof, motor apparatus disposed at the top of said bridge, and driving gear operative between said motor apparatus and said eccentrics, the latter being operative to impart to said carrier quickly repeated forward and backward movements with intervening upward and downward movements on said carriage.

5. A plough according to claim 1 and in which the carriage is a structure in the form of a bridge disposed to extend normal to the direction of the face, said structure comprising, at the top of the bridge, a motor apparatus geared with the means which operate the carrier for the series of cutters, and, at the face end of said bridge, the wedge formation, on which said carrier is mounted, is substantially parallel to the face.

6. A plough according to claim 1, further characterized in that the wedge formation of the plough comprises a renewable wedging blade which is straight in vertical section and, in plan, extends curvedly at an incline outwardly and rearwardly from the forward edge of such wedge formation, said edge extending substantially par-

allel to, and in the region of, the series of cutters and for the preponderant part of the height of the face.
